UNITED STATES PATENT OFFICE.

GEORGE C. DIEHL AND JEREMIAH A. BARBER, OF BUTLER, INDIANA.

CARBURETER.

SPECIFICATION forming part of Letters Patent No. 700,307, dated May 20, 1902.

Application filed February 15, 1901. Serial No. 47,478. (No model.)

To all whom it may concern:

Be it known that we, GEORGE C. DIEHL and JEREMIAH A. BARBER, citizens of the United States, residing at Butler, in the county of 5 Dekalb and State of Indiana, have invented a new and useful Gasolene-Gas-Generating Apparatus, of which the following is a specification.

Our invention is an improved apparatus for 10 generating gasolene-gas for illuminating purposes; and it consists in the peculiar construction and combination of devices hereinafter fully set forth, and pointed out in the claims.

One object of our invention is to provide 15 means for heating the body of gasolene in the reservoir by passing heated gas through a pipe therein, thereby expanding the body of gasolene and facilitating the flow of gasolene through the feed-pipe to the gas generator or 20 vaporizer.

A further object of our invention is to effect 25 improvements in the construction of the gas generator or vaporizer.

In the accompanying drawings, Figure 1 is 30 partly a sectional view and partly an elevation of a gasolene-gas-generating apparatus embodying our improvements. Fig. 2 is a detail sectional view of the gas-generator. Fig. 3 is a perspective view of a modified form of our invention.

The gasolene-feed pipe 1 leads upward from a gasolene-reservoir 2; the lower end of the said pipe being submerged in the body of the gasolene in said reservoir, and at the upper 35 end of the said pipe is a circular generating or vaporizing chamber 3, the said pipe communicating with the central portion of said chamber on the lower side thereof. The gas-service pipe 4 is coupled to a gas-pipe 5, which 40 leads from the upper side of the generating-chamber and on which is supported a horizontally-disposed concavo-convex shield 6. A needle-valve 7 is disposed in the pipe 5. A gas-pipe 8 leads from one side of the vaporizing or generating chamber and is provided 45 with a needle-valve 9, the point of which is disposed opposite the mixing-tube or intake 10, that leads to an annular space 11, formed between the outer circular casing 12 and the 50 perforated interior tube 13, which constitutes the subflame-burner 14. Said burner is disposed concentrically on the feed-pipe 1, the

bottom plate 15 of said subflame-burner being supported on a ring 16, which is adjustable on the pipe 1 and may be secured thereon by any suitable means, a screw 17 being here shown for this purpose. A drip-cup 18, to contain gasolene for initially heating the generating apparatus and burner, is supported by the subflame-burner and disposed under the pipe 8. Any suitable means may be employed for coupling the pipe 5 to the gas-service pipe 4.

A pipe 18a leads from the gas-service pipe 4 through the body of gasolene in the reservoir 2. The function of the said pipe 18 is to circulate hot gas from the gas-service pipe through the body of the gasolene to heat the latter, expand the same, and facilitate the flow thereof from the gasolene-reservoir to the 70 generator. A suitable air-compressor, which is indicated diagrammatically at 19 in Fig. 1, is connected to the upper portion of the gasolene-reservoir and serves to compress air above the body of gasolene in the reservoir, 75 and thereby cause the gasolene to be fed to the generator or vaporizer, as will be understood. The gas-service pipe leads to suitable illuminating-burners 21.

The operation of our invention is as follows: 80 The generator and subflame-burner being first initially heated in the usual well-known manner or in any other suitable manner, the gasolene is converted into gas or vapor in the chamber 3 and passes therefrom into the gas-service pipe which leads to the burner. A portion of the gas or vapor passes through the pipe 8 and is directed by the needle-valve 9 through the mixing-tube 10 into the annular space in the subflame-burner formed between the outer casing thereof and the perforated tube 13. As the gas is discharged 85 through the mixing-tube into the subflame-burner which surrounds the feed-pipe 1 it is commingled with air and rendered combustible and on being ignited discharges a plurality of jets inwardly against the upper portion of the pipe 1, thereby heating the said pipe, and as the generating-chamber is directly above the subflame-burner said generating-chamber is also directly heated on its 90 lower side, the upper side of said generating-chamber being heated by radiation from the shield 6.

In Fig. 3 of the drawings we show a modified form of our invention, in which the reservoir is a vertically-disposed tank having a false bottom 22 at a suitable distance from the lower end thereof. The generator and subflame-burner are placed on one side of the tank and at a point lower than the false bottom 22 and the feed-pipe 1 leads downward from the body of gasoline to the generator, the weight of the body of gasoline and the hydrostatic pressure thereof being utilized in feeding the generator. In this form of our invention the tube 18^a (shown in Fig. 1) is dispensed with, and the service-pipe 4 leads from the generator into the tank and upward through the body of gasoline or other liquid hydrocarbon therein and its heat utilized to raise the temperature of the body of liquid hydrocarbon, as will be understood. While our improved apparatus has been hereinbefore described as efficient in generating gasoline-gas for illuminating purposes, it will be understood that the gas generated thereby may also be used for heating and cooking purposes in common wood or coal stoves.

The shield 6, in addition to its function in reflecting heat downward on the vaporizing-chamber, prevents the ignition of the gas from the subflame-burner.

Having thus described our invention, we claim—

1. In a gasoline-gas generator, the combination of a generator, a feed-pipe leading thereto, a subflame-burner in operative relation to said generator, a shield over the latter, and a service-pipe having its inner end disposed opposite the discharge of the generator and above said shield, substantially as described. 35

2. The combination of a generator, a reservoir for gasoline, a feed-pipe leading from said reservoir to said generator, a subflame-burner disposed under the generator, a shield above the latter and through which the vapor 45 discharge of the generator passes, and a service-pipe, having its open, inner end disposed above said shield opposite and above said vapor discharge of said generator, said service-pipe passing through the body of gasoline 50 in the said reservoir, substantially as described.

In testimony that we claim the foregoing as our own we have hereto affixed our signatures in the presence of two witnesses.

GEORGE C. DIEHL.
JEREMIAH A. BARBER.
